BY
Charles H. Wilson, ATTORNEY

UNITED STATES PATENT OFFICE.

LEON S. BRACH, OF NEWARK, NEW JERSEY.

THERMOMETER.

1,403,228.

Specification of Letters Patent. Patented Jan. 10, 1922.

Application filed April 20, 1921. Serial No. 462,849.

To all whom it may concern:

Be it known that I, LEON S. BRACH, residing at Newark, in the county of Essex and State of New Jersey, have invented certain new and useful Improvements in Thermometers, of which the following is a specification.

This invention relates to new and improved temperature indicating devices, and one of the objects of the invention is to provide a device of the above character which will give an accurate indication of temperature of a room or compartment, and which will also be attractive in appearance so that it may be used as an ornament for a dressing table, chiffonier, or the like.

Another object of the invention is to provide a device of the above character, which will give a special indication of when the room or compartment is either too hot or too cold.

Other objects and aims of the invention, more or less specific than those referred to above will be in part obvious and in part pointed out in the course of the following description of the elements, combinations, arrangements of parts and applications of principles, constituting the invention; and the scope of protection contemplated will be indicated in the appended claims.

In the accompanying drawings, wherein I have illustrated preferred forms of embodiment of my invention:

Figure 1 is an elevational view of one embodiment of the invention.

Figure 2 is a vertical cross-section of Figure 1.

Figure 3 is a vertical sectional view of another embodiment of my invention.

Figure 4 is a side elevational view of the embodiment of my invention shown in Figure 3.

Figure 5 is a view in elevation of another embodiment of my invention.

Referring now to the drawings, wherein similar reference characters refer to similar parts throughout the several views thereof, and particularly to the embodiments of my invention shown in Figures 1 to 5 inclusive, the reference numeral 1 denotes a suitable base member or support for the device, which is preferably of an ornamental character, as shown in all the figures of the drawings. This base member supports a casing 2 including a hollow rectangularly formed member 4,

which in the present instance is provided with a removable cover portion 3.

The member 4, which as shown in Figures 1, 2 and 3 of the drawing, extends entirely around the casing 2 forming a part of the inner surface thereof. Pivoted intermediate the ends of the member 4 is a shaft 5, and mounted upon this shaft is a dial member 6, which dial member is circular in form and has the depending flange 7.

The flange 7 of the dial 6 is provided with the indicating numbers or scale 8, which numbers are preferably positioned entirely around the flange 7 of the dial. Fastened to a post 9 is one end of a spirally formed thermostatic member 10, the opposite end of said member being made fast to the shaft 5, said thermostatic member being preferably coiled about said shaft, as clearly shown in Figure 3 of the drawings.

The thermostatic member 10 is preferably formed of a thin strip of metal having such qualities that it is adapted to expand or contract in accordance with the varying degrees of temperature, whereby said expansion or contraction of the spirally formed member will cause a rotated movement of the dial. The spirally formed thermostatic member and dial being of course so relatively proportioned that the latter will be caused to rotate in a manner proportioned to the rising or falling of the mercury in the ordinary form thermometer.

The casing 2 is provided in its side wall as shown in Figures 1 and 4, with an elongated substantially rectangular slot 11, through which the numbers of the dial are visible, an arrow, as at 12, being provided, and with which the numbers on the dial associate to indicate the temperature.

In Figure 1 the base member is fastened to one of the flat sides of the casing 2, so that the casing stands horizontally, while in the embodiments of my invention shown in Figures 3, 4 and 5, the casing is supported upon its curved exterior surface, so that it stands upright. In Figure 5 the numerals of the dial are positioned upon the face thereof, rather than upon the flange, so that they are exposed through a curved aperture 13.

In both of the above described embodiments of my invention I have provided means on the dial or scale which will give a distinct indication when the temperature of the room or compartment is above or be-

low certain degrees of temperature, or above or below what is generally accepted as a normal temperature, say a temperature ranging from 50 to 80 degrees. This is accomplished by having the numerals including 5, and those below that number printed in one color, and having the numerals above 80, and including that number, printed in another color, the numerals 60 and 70 being 10 printed still a different color. Thus in the present instance the "60" and "70" being printed in plain black, the numerals below that being printed in blue, and the numbers above 70 being printed in red.

15 Provided in the walls of the casing is a plurality of apertures 33, and also located in the dials in all the embodiments of the invention shown herein is a plurality of apertures 34. The object of providing these 20 apertures is to permit a free access to the air in the room or compartment, where the device is used, to the interior of said device, so that the thermostatic operating device may be at all times in direct contact, or 25 under the direct influence of the room temperature.

It will further be seen that the user of the device can quickly ascertain whether the room or compartment is above or below what 30 is generally accepted as the normal temperature.

It will accordingly be seen that I have provided a construction well adapted to attain, among others, all the ends and objects above 35 pointed out, in a simple yet efficient manner.

As many changes could be made in this construction without departing from the scope of the following claims, it is intended that all matter contained in the above 40 description or shown in the accompanying drawing shall be interpreted as illustrative only and not in a limiting sense.

Having thus described my invention what I claim as new and desire to secure by Letters Patent is:

1. In a device of the class described, in combination, a casing provided with an observation opening, a rotatable dial having its axis journaled in opposed walls of said 50 casing, a thermostatic member connected with the axis of said dial adapted to operate the same, said dial being exposed through said casing, and said casing and said dial being provided with a plurality of apertures 55 so that air may freely circulate therethrough.

2. In a device of the class described, in combination, a casing, a shaft, bearing points for said shaft in opposed walls of said casing, a dial mounted upon said shaft, a thermostatic member having one end connected to said shaft, and the opposite end connected to a fixed support, said dial and said thermostatic member being located intermediate the points of bearing of said shaft. 60

3. In a device of the class described, in combination, a casing having opposed walls, a shaft rotatably mounted in the opposed walls of said casing, a thermostatic member encircling said shaft, a dial mounted upon said shaft, said dial having a face portion which overhangs a portion of said shaft and partially encloses said thermostatic member, and said thermostatic member having one end thereof attached to a fixed support, 70 and its opposite end attached to the axis of said dial. 75

4. In a device of the class described, in combination, a casing, a shaft rotatably supported intermediate opposed walls of said 80 casing, a cylindrically formed member fixedly mounted upon said shaft, a thermostatic member encircling said shaft and having one end attached to a fixed support, and its opposite end to said shaft, said cylindrically formed member having a downwardly extending flange which encircles the upper end of said shaft to partially enclose said thermostatic member, and a scale formed upon the outer face of said flange. 90

5. A device of the class described, in combination, a casing having opposed walls, a shaft journalled in said walls, a cylindrically formed rotatable member through which said shaft extends, and upon which it is 95 fixed against relative rotative movement, a thermostatic member encircling said shaft and having one end thereof attached to a fixed support and its opposite end attached to said shaft, said cylindrically formed member having a laterally extending flange, and a scale formed on the outer face of said flange. 100

In testimony whereof I affix my signature in the presence of two witnesses.

LEON S. BRACH.
